CLAIM

The ornamental design for a pendant, as shown and described.

DESCRIPTION

FIG. 1 is a front view of a pendant showing my new design;
 FIG. 2 is a back view thereof;
 FIG. 3 is a perspective view thereof;
 FIG. 4 is a top view thereof;
 FIG. 5 is a bottom view thereof;
 FIG. 6 is a left side view thereof; and,
 FIG. 7 is a right side view thereof.
 The broken lines shown in FIG. 2 represent portions of the
 pendant which form no part of the claimed design.
